UNITED STATES PATENT OFFICE

LOUIS E. ENDSLEY, OF PITTSBURGH, PENNSYLVANIA

TANK CAR STRUCTURE

Application filed March 20, 1931. Serial No. 523,970.

My invention relates to railway tank car structures and more particularly to the body portions thereof.

In this application, I describe and claim a structure constituting an improvement upon my Patent No. 1,790,855, issued February 3, 1931. In said patent, a dome is shown at each end of a tank car, the arrangement being such that upon impacts or shocks resulting during transportation or switching of the cars, portions of the liquid contents will enter one of the domes, thus permitting temporary displacement of substantially the entire liquid contents of the car body, and also providing an air cushion in the dome. Thus, if the forward movement of a car is suddenly checked, the liquid contents thereof will tend to shift toward the front end of the car, but the usual thrust resulting from such tendency will be reduced or counteracted, by reason of the fact that a portion of the liquid will be deflected into the dome at the front end of the car, and at the same time, be cushioned by the entrapped air within the dome. The dome at the other end of the car will serve a similar function when thrusts occur in the opposite direction.

One object of the present invention is to provide means for venting the said domes near the ends of the cars to the atmosphere, at points remote from the domes themselves, to thereby permit of the establishment of greater air pressure within these domes upon displacement of the liquid lading.

Another object of this invention is to provide means for more effectively entrapping or confining air within the said domes.

A further object of my invention is to provide means for reducing reactive forces within the tank body, after the liquid lading has been displaced in one direction through buffing stresses on the car body.

Still another object of my invention is to provide a tank car structure of generally simplified and improved form.

Some of the forms which my invention may take are shown in the accompanying drawing, wherein Figure 1 is a side elevational view of a railway tank car; Fig. 2 is a fragmentary sectional view thereof, on an en-

larged scale; Fig. 3 is a view taken on the line III—III of Fig. 2; Fig. 4 is a view taken on the line IV—IV of Fig. 2, and Fig. 5 shows a modification of the structure of Fig. 3.

Reference is made to the specification of my previous patent for various details regarding the extent of yielding resistance offered to shocks resulting from buffing strains, and they need not be here repeated.

The car is shown as having an under frame 6, draft gears 3, and trucks, which may be of the usual construction. However, the car body or tank 7 not only has the usual central dome 8, but end domes 9 and 10. The dome 8 is provided with the usual relief valve 11 and a valve-controlled drain pipe 12 is provided at the bottom of the car body.

The domes 9 and 10 communicate with the interior of the tank 7, but are closed at their upper portions, to permit the effective confinement of air within the domes when endwise thrusts on the car cause displacement of the liquid contents of the car. In normal use, the tank 7 is completely filled with liquid except for the spaces within the domes, so that when an endwise thrust is imposed on the car, say from the left hand end toward the right hand end thereof, a portion of the liquid will be caused to enter the dome 10, thus permitting some displacement of substantially the entire liquid contents of the tank.

This displacement of the liquid is yieldably resisted by the weight of the liquid which enters the dome 10 and by the cushioning effect of the air entrapped within the dome. A similar effect will be produced by the dome 9 when endwise thrusts are imposed in the opposite direction.

It is desirable that gases be vented from the domes 9 and 10, without materially affecting their air-confining functions. To this end, I provide pipes 14 each of which communicates at its ends with the lower portion of one of the domes 9 and 10, and at its other end with the dome 8.

These pipes are preferably positioned slightly above the normal liquid level but may be slightly below such level and still permit the venting of gases from the domes.

9 and 10 and through the blow-off-cocks or relief valves 11. When the fluid enters the dome 10, for example, it will, of course, rise above the pipe 14 and compress the air within such dome.

In order to more effectively entrap the air within the domes 9 and 10, through surging movement of the liquid lading, I provide skirts or baffle plates 15 of semi-circular form, which extend downwardly from those sides of the domes which lie next to the mid portion of the car. These plates 15 are of narrow vertical width and short length relative to the diameter of the car, so that they will not unduly restrict movement of the liquid lading, but will overcome tendency of the air to be forced from the dome toward the central portion of the car in the direction indicated by the arrow 16 in Fig. 2.

In order to reduce reactive force following an end thrust on the car, I provide in each of the domes 9 and 10 hinged plates 17 and 18 that function as flap valves or check valves. These plates are normally held against their seats 19 and 20, respectively, by springs 21, that are carried by pintles or rods 22 upon which the valves are pivotally mounted.

The valves 17 and 18 are moved upwardly by flow of liquid into the domes, as indicated by dotted lines in Fig. 2, the springs 21 returning the valves to their closed positions quickly after flow of fluid into the dome has stopped, thus confining a volume of liquid within the dome and preventing it suddenly flowing back to the body of the tank car under the action of gravity and by the pressure of the confined air. The entrapped liquid will be permitted to return slowly to the main body of liquid by leakage past the valves 17 and 18.

It will be obvious that the normally reactive forces are thus materially reduced or retarded.

As the pipes 14 are connected to the end domes below the check valves, there will be no surge of liquid therethrough from the end domes, except the blow be a very small one. That is, if under a heavy blow, the retaining valves trap a large percentage of oil and a low volume of air or gas, this will not flow into the center dome. Of course, under the initial impact or under very small impacts, or at the beginning of the large impact, there may be some liquid and a small amount of gas flow back into the pipe 14, but when the pipe 14 fills up to the center dome, the liquid moving forward from the other end of the car will have the same retaining force as one-half the contents of the car would have, because the liquid is all tending to go in the same direction and therefore will have the same pressure at the forward dome end as the liquid has underneath, and no flow will be produced.

Referring now to Fig. 5, I show a dome

similar to the domes 9 and 10, but which is provided with a series of check valves 24 instead of the flap valves 17 and 18. These valves 24 are yieldably held against their seats by means of springs 25 interposed between the heads of the valve stems and the valve stem guides 26. A dished plate 27 is secured in the dome and provided with cut-out portions that serve as passageways for liquid entering the dome, and the plate serving as a seat for the valves 24. The plate 27, being dished downwardly, has greater strength to resist pressure from within the dome than if it were flat.

The check valves 24 in one of the end domes will, of course, be moved upwardly if an impact of sufficient force is imposed against either end of the car, and oil will surge or move up through these check valves 24. If this blow is sufficient to cause the oil to go up under a heavy pressure, when the force is removed from that end of the car, a surge would be produced by this entrapped air or gas, but for the check valves which will immediately close upon a reverse movement of the liquid, and they will hold this entrapped air or gas for a sufficient time to prevent a surge toward the other dome. This air pressure can be relieved gradually by predetermined sizes of holes in the check valves or in the plate 27.

As the rules or requirements for tank cars specify a given percentage of open space in the dome above the liquid, by the use of pipe 14 from the two end domes to the center dome, the center dome can be much smaller than now made, because of the extra capacity furnished by the two end domes. I contemplate also that the central dome may be provided with check valves similar to the valves of Figs. 2 to 5, where conditions render such structure desirable.

I claim as my invention:—

1. A vehicle having a tank-like body of elongated form disposed in parallelism with the line of movement of the vehicle, a dome extending upwardly from a point adjacent to each end of the said body, the said domes having communication with the interior of the body to permit displacement of liquid lading, and check valve devices permitting relatively free flow of liquid into said domes, but retarding backflow therefrom.

2. A vehicle having a tank-like body of elongated form disposed in parallelism with the line of movement of the vehicle, a dome extending upwardly from a point adjacent to each end of the said body, the said domes having communication with the interior of the body to permit displacement of liquid lading, and vent pipes each connected at one end to the lower portion of one of the domes and having means adjacent to its other end for communication with the atmosphere.

3. A vehicle having a tank-like body of

elongated form disposed in parallelism with the line of movement of the vehicle, a dome extending upwardly from a point adjacent to the middle of the body, a dome extending upwardly from a point adjacent to each end of the said body, pipes communicating with the lower portions of the last-named domes and with the first-named dome, and a venting device on the first-named dome.

10 4. A vehicle having a tank-like body of elongated form disposed in parallelism with the line of movement of the vehicle, a dome extending upwardly from a point adjacent to the middle of the body, a dome extending upwardly from a point adjacent to each end of the said body, pipes communicating with the lower portions of the last-named domes, and with the lower portion of the first-named dome.

15 5. A vehicle having a tank-like body of elongated form disposed in parallelism with the line of movement of the vehicle, a chamber for confining air and for utilizing the said air to cushion movement of liquid within the said body, the said chamber communicating with the interior of said body and being of sufficient area to permit displacement of such quantity of liquid lading as to materially dampen buffering forces, and a baffle 20 plate depending from a point adjacent to the lower end of the chamber, the plate being of small vertical dimension relative to the diameter of the tank.

25 6. A vehicle having a tank-like body of elongated form disposed in parallelism with the line of movement of the vehicle, a chamber for confining air and for utilizing the said air to cushion movement of liquid within the said body, the said chamber communicating with the interior of said body and being of sufficient area to permit displacement of such quantity of liquid lading as to materially dampen buffering forces, and a baffle 30 plate depending from a point adjacent to the lower end of the chamber, the plate being of narrow width relative to the diameter of the tank, and disposed transversely of the car body, the shortest distance between the ends of the plates being not materially in excess 35 of the diameter of the chamber.

40 7. A vehicle having a tank-like body of elongated form disposed in parallelism with the line of movement of the vehicle, a chamber for confining air and for utilizing the said air to cushion movement of liquid within the said body, the said chamber communicating with the interior of said body and being of sufficient area to permit displacement 45 of such quantity of liquid lading as to materially dampen buffering forces, and a baffle plate depending from a point adjacent to the lower end of the chamber, the plate being of narrow width relative to the diameter of the tank, and being curved coaxially of the cham- 50

ber through a distance not materially greater than one-half of a circle.

8. A vehicle having a tank-like body of elongated form disposed in parallelism with the line of movement of the vehicle, a chamber extending above the normal liquid level in the tank, for confining air and for utilizing the said air to cushion movement of liquid within the said body, the said chamber communicating with the interior of said body 70 and being of sufficient area to permit displacement of such quantity of liquid lading as to materially dampen buffering forces, and means operative to permit relatively free flow of liquid into said chamber but retarding backflow therefrom.

75 9. A vehicle having a tank-like body of elongated form disposed in parallelism with the line of movement of the vehicle, an air-confining chamber disposed above the normal liquid level and communicating with the tank-like body, the chamber being of sufficient area to permit displacement of such quantity of liquid lading as to materially dampen buffering stresses, and a venting device leading from the lower portion of said chamber at a point adjacent to the normal liquid level in the tank.

80 10. A vehicle having a tank-like body of elongated form disposed in parallelism with the line of movement of the vehicle, a chamber disposed above and communicating with the interior of said body, the said chamber communicating with the interior of the said body and being of sufficient area to permit displacement of such quantity of liquid lading as to materially dampen buffering forces, and means operative to permit relatively free flow of liquid into said chamber but retarding 85 backflow therefrom.

85 In testimony whereof I, the said LOUIS E. ENDSLEY, have hereunto set my hand.
